UNITED STATES PATENT OFFICE

101,130

DESIGN FOR A PENCIL CLIP OR SIMILAR ARTICLE

John P. Lynn, Chicago, Ill., assignor to Dur-O-Lite Pencil Company, Melrose Park, Ill., a corporation of Delaware

Application July 1, 1936, Serial No. 63,606

Term of patent 7 years

To all whom it may concern:

Be it known that I, John P. Lynn, a citizen of the United States, residing at Chicago, in the county of Cook and State of Illinois, have invented a new, original, and ornamental Design for a Pencil Clip or Similar Article, of which the following is a specification, reference being had to the accompanying drawing, forming a part thereof.

Figure 1 is a front elevation of a pencil clip or similar article showing my new design;

Fig. 2 is a side elevation; and Fig. 3 is a rear elevation showing the clip. The dotted lines in the three figures indicate a portion of the clip which in service is completely hidden.

I claim:

The ornamental design for a pencil clip or similar article, substantially as shown and described.

JOHN P. LYNN.
